UNITED STATES PATENT OFFICE.

WILLIAM R. HOLDER, OF VERBENA, ALABAMA.

LUBRICATOR.

SPECIFICATION forming part of Letters Patent No. 321,436, dated July 7, 1885.

Application filed March 25, 1885. (No model.)

To all whom it may concern:

Be it known that I, WILLIAM R. HOLDER, a citizen of the United States, residing at Verbena, in the county of Chilton and State of Alabama, have invented certain new and useful Improvements in Lubricators, of which the following is a specification, reference being had therein to the accompanying drawings.

10 This invention relates to lubricators provided with a glass gage or tube through which the operation can be watched; and it consists in certain improvements in the construction of the same, as hereinafter described, and 15 specifically set forth in the claim.

In the accompanying drawings, Figure 1 represents in vertical section a lubricator constructed in accordance with my invention. Fig. 2 is a horizontal section of a three-way 20 cock used therewith.

Like letters represent like parts in all the figures.

A represents the oil-reservoir. It is connected at its lower portion by means of a 15 pipe, A², with the pipe G, conducting steam from the boiler to the engine. The pipe A² is provided with a valve, a, adjacent to the reservoir to regulate the amount of incoming 20 steam. The bottom portion of the reservoir 30 A is provided with a downward passage, B, leading to the drip-cock B', attached to the shell of the reservoir A. In the center of the bottom of the reservoir A is a recess or 35 chamber, C, communicating with a passage, C', into which is received one end of the pipe C², leading to the lower end of the glass tube D. Within the upper portion of the reservoir there is a horizontal spider or 40 guide, A³, for the upper end of the tube E, while its lower end enters the recess or chamber C, and is supported on the bottom of the reservoir by the flange E'. The guide A³ is provided with a series of perforations, a', 45 for the passage of oil. In the upper portion of the reservoir A and under the guide A³ is a pipe, D', which connects the reservoir with the steam-pipe G, and upon said pipe D' is a plug-valve, F, the lower portion of 50 which receives the upper end of the glass

tube D and retains it in position. The plug F' is a three-way plug to permit the use of the apparatus even after breakage of the glass tube, as will be hereinafter described. The cover H is screwed into the shell of the reservoir A at h, and carries at its upper end a stuffing-box, through which a screw-threaded stem, H', passes, and its conical lower end is so formed that it can take a seat in the opening at the top of the tube E, so that the amount of oil fed by the lubricator can be regulated by the adjustment of said screw-threaded stem H'.

The operation of the lubricator is as follows: Water having been placed in the glass tube D either before connecting the lubricator to the pipe G or from condensation of a small current of steam passed through the apparatus, the plug F' is given half a turn from the position shown in Fig. 2, and either the valve a or a' is closed. The top of the reservoir is then opened and the latter filled with tallow or any suitable oil to lubricate the cylinder. The cap is then replaced and the stem H' screwed down until it rests upon the end 75 of the tube E. The valve a is then opened wide and the valve a' just enough to operate the device. The stem H' is then slightly unscrewed and a portion of the oil floating upon the condensed water in the reservoir first descends in the tube E, and drops of oil are seen to ascend through the water in the glass D. The plug F' is then turned, as shown in Fig. 2, or enough to admit the oil into the steam-pipe G; but the supply is controlled mainly 80 by the screw-threaded stem H'. The plug-valve F is so constructed that in case the glass tube D is broken the oil can be automatically fed direct from the reservoir A through the discharge-pipe D' into the steam-pipe G by 85 giving the plug F' one quarter turn from the position shown in Fig. 2, and closing the lower end of said plug.

When it is desired to refill the reservoir with oil, &c., the cover H is removed and the drip-cock B' opened to allow the water of condensation to escape from the reservoir.

Having now fully described my invention, I claim—

A lubricator consisting of the reservoir A, 10

having the steam-pipe A², the central tube, E, secured to the bottom of said reservoir, the cover H, and its stuffing-box H², with the screw-threaded stem H', the lateral pipes C² and D', connected by a glass tube, and the plug-valve F, adapted to control either one of said pipes, substantially as and for the purpose described.

In testimony whereof I affix my signature in presence of two witnesses.

WILLIAM R. HOLDER.
